HARRY JACOBS Inventor
HANNAH JACOBS.

UNITED STATES PATENT OFFICE.

HARRY JACOBS AND HANNAH JACOBS, OF NEW YORK, N. Y.

PIPING-STEM.

1,360,644.

Specification of Letters Patent. Patented Nov. 30, 1920.

Application filed December 26, 1919. Serial No. 347,421.

To all whom it may concern:

Be it known that we, HARRY JACOBS and HANNAH JACOBS, citizens of the United States, and residents of New York, in the county of Kings and State of New York, have invented certain new and useful Improvements in Piping-Stems, of which the following is a specification.

This invention relates to improvements 10 in piping or winding stems which are employed as a means for curling and holding the hair during the process of waving and drying.

The object of this invention is to provide 15 a device which will by its use, reduce the time necessary to prepare the hair to effect a permanent wave.

This object is accomplished by the device 20 illustrated in the accompanying drawing, in which—

Figure 1 is a side view of the device, and Fig. 2 is a section along the line 2—2.

Referring in detail to the parts, 1 designates a hollow member having perforations 25 2 formed therein and which is provided with a holding member 3 pivotally connected to the hollow member at 4 and formed with a locking means 5 which is adapted to engage one end of the hollow member to 30 hold the hair wound thereon.

In practice, the hollow member is filled with any approved chemical mixture commonly used in the process of waving hair.

The hair is then wound upon the said hollow member and held in place thereon by 35 means of the holding member.

Moisture is then applied sufficiently to dampen the mixture contained within the hollow member allowing the dissolved mixture to permeate the hair. Heat is then 40 applied in the usual way until the hair is dried.

Various modified forms may be employed without departing from the spirit of this invention, which is therefore not limited to 45 the particular construction shown.

Having thus described the invention, it is claimed;

1. In a hair waving stem, a tapered, tubular member having a chemical containing 50 compartment formed therein and perforations formed thereon to permit the chemical within the compartment to act upon the hair wound upon the stem.

2. In a hair winding stem, a tubular chemical containing member having perforations formed thereon to permit contact of the chemical, contained within the tube, with the hair wound thereon and means for holding 55 the hair upon the tube. 60

Signed at New York, in the county of Kings and State of New York, this 20th day of December, A. D. 1919.

HARRY JACOBS.
